UNITED STATES PATENT OFFICE.

GEORGE D. BATEMAN, OF PINCKNEYVILLE, ILLINOIS.

BOOT-TREE.

SPECIFICATION forming part of Letters Patent No. 319,667, dated June 9, 1885.

Application filed December 22, 1884. (No model.)

To all whom it may concern:

Be it known that I, GEORGE D. BATEMAN, of Pinekneyville, in the county of Perry and State of Illinois, have invented certain new and useful Improvements in Boot-Trees; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved boot-tree. Fig. 2 is a vertical sectional view of the same. Fig. 3 is a horizontal transverse sectional view, and Fig. 4 is a detail view showing the parts composing my improved boot-tree detached from each other.

The same letters refer to the same parts in all the figures.

This invention relates to boot-trees; and it has for its object to provide a device which shall possess superior advantages in point of simplicity, durability, inexpensiveness, ease of operation, and general efficiency.

With these ends in view the invention consists in the improved construction and arrangement of parts, which will be hereinafter fully described, and particularly pointed out in the claim.

In the drawings hereto annexed, A designates the front section of my improved boot-tree, which is provided at its lower end with the detachable foot portion B, which is connected thereto by a dovetailed flange, C, adapted to enter a corresponding dovetailed slot or groove, D, in the lower end of the section A, as shown.

E is the middle section, which is provided with a transverse longitudinal slot, F, extending from its lower end for the greater portion of its length toward the top. Said slot forms a way or guide for a wedge-shaped key, G, which is provided with a longitudinal screw-threaded perforation or bearing, H, for an operating-screw, I, which is swiveled or journaled in a suitable bearing, J, at the upper end of the section E. The upper end of the screw I is provided with a collar or flange, K, between which and the bearing H is arranged a latch or turn-button, L.

The sides of the middle section, E, of my improved boot-tree are provided with rearwardly-extending flanges M M, between which is fitted the rear section, N, the lower end of which has an inclined or wedge-shaped recess, O, adapted to receive and engage the face of the wedge-shaped key or block G, which is vertically adjustable by the screw I, as stated. The upper end of the rear section, N, has a set-screw or thumb-screw, P, bearing against the upper end of the middle section, as shown, and serving, when desired, to spread or expand the upper end of the boot-tree.

It will be noticed that the grooves Q Q in the sides of the key or wedge G, which form the bearings for the sides of the slot F of the middle section, E, are somewhat wider than the sides of the said slot, thereby permitting a slight play or motion of the said wedge-shaped block. By this construction it will be seen that when the key or wedge is raised it will act against both the front and rear sections of the boot-tree, and thus expand the said sections, and hence the front and rear parts of the boot simultaneously, the advantages of which will be readily understood. It will be noticed, however, that the expansion of the front section is comparatively slight, while the rear section, which is principally acted upon by the wedge-shaped key, is covered and guarded by the flanges M of the middle section, which serve to form a solid joint or connection and enable the seam to be set up perfectly. The upper end of the boot-tree is expanded by the set-screw P.

The advantages of my improved boot-tree will be readily understood from the foregoing description, taken in connection with the drawings hereto annexed. It is simple in construction, easily applied, and owing to its peculiar construction it may, after use, be readily detached or removed from the boot by simply loosening the thumb-screw P and lowering the wedge G, without the employment of more force than is necessary simply to lift the several sections of the tree out of the boot-leg.

It is obvious that the several parts of the device may be made of metal, wood, or of any other material or combination of materials that may be found useful for the purpose. The invention, as will be readily seen, is also

susceptible of various changes with regard to the construction of details, and I would have it understood that I reserve to myself the right to all such changes and modifications as may 5 be resorted to without departing from the spirit of my invention.

Having thus described my invention, I claim and desire to secure by Letters Patent of the United States—

- 10 In a boot-tree, the combination of the middle section having a slot and a vertically-movable key or wedge, a swiveled operating-screw having a latch or turn-button, and the front

and rear expanding sections, the latter of which is provided at its lower end with a 15 wedge-shaped or beveled recess and at its upper end with a thumb-screw, substantially as and for the purpose herein shown and specified.

In testimony that I claim the foregoing as 20 my own I have hereunto affixed my signature in presence of two witnesses.

GEORGE D. BATEMAN.
